DESIGN FOR A CASING FOR A COOLER FOR FLUIDS

Carl L. Trier, Baltimore, Md., assignor to Cherry-Burrell Corporation, Wilmington, Del., a corporation

Application April 3, 1939, Serial No. 84,005

Term of patent 14 years

To all whom it may concern:

Be it known that I, Carl L. Trier, a citizen of the United States, residing at Baltimore, in the county of Baltimore and State of Maryland, have invented a new, original, and ornamental Design for a Casing for a Cooler for Fluids, of which the following is a specification, reference being had to the accompanying drawing, forming part thereof.

In the drawing:

Fig. 1 is a perspective view of a casing for a cooler for fluids showing my new design; and

Fig. 2 is a top plan view thereof.

I claim:

The ornamental design for a casing for a cooler for fluids, as shown.

CARL L. TRIER.
